PATTERN BOARD

Harold O. Capps, Houston, Tex.

Application July 28, 1945, Serial No. 607,612

1 Claim. (Cl. 22—157)

This invention relates to a mold and has more particular relation to the pattern board of the mold.

An object of the invention is to provide, in a mold, a novel type of pattern board on one side of which two halves of the pattern of a casting are fastened and which serve simultaneously as the cope and drag parts of a molding flask.

Another object is to provide a pattern board comprising a metal frame and a wooden plate mounted therein with releasable means for securing the plate in the frame and means for accurately centering and maintaining the plate in an exact selected position therein.

Another object is to provide, in combination with a pattern board, a flask and means whereby the flask may be maintained accurately in the required relation with the board.

With the above and other objects in view this invention has particular relation to certain novel features of construction, arrangement of parts and use, an example of which is given in this specification and illustrated in the accompanying drawings, wherein:

Figure 1 is a top plan view of the pattern board.

Figure 2 is a bottom plan view, showing one of the clamp dogs in released position.

Figure 3 is a longitudinal sectional view of the complete mold taken on the line 3—3 of Figure 2.

Figure 4 is a fragmentary longitudinal sectional view taken on the line 4—4 of Figure 2, and

Figure 5 is a cross sectional view taken on the line 5—5 of Figure 3.

Referring more particularly to the drawings the numeral 1 designates a metal frame, preferably, rectangular in form and having an inside flange 2 extending all the way around the frame and spaced from the top thereof.

The frame also has the outwardly turned end lugs 3, 3 with the upstanding posts 4, 4 secured thereto.

Seated on the flange 2 there is a wooden plate 5 which fits closely in the frame and whose upper face is flush with the top of the frame; the plate, of course, may be made of other suitable material.

Secured to the under side of the plate 5, at one end, there is a transverse metal clamp 6 whose outer margin 7 is spaced from the plate 5. This margin of the clamp engages underneath the adjacent end flange of the frame, said flange having a countersunk portion 8 to receive said free margin of the clamp 7.

Spaced from the other end of the plate 5, and secured thereto, there is a transverse metal clamp 9 whose outer margin 10 is spaced from said plate.

The margins 7 and 10 of said clamps have the central, outwardly flared notches 11 and 12 and secured to the ends of the frame are the inwardly projecting, tapering, lugs 13, 14 which fit snugly in said notches and hold the plate 5 centered in the frame 1.

10 Pivoted to the end of the frame in front of the clamp 9 there are the clamp dogs 15, 15 whose free ends are engageable with, and releasable from, the margin 10, of the clamp 9. The pivoted ends of these dogs have the outwardly turned handles 16, 16 preferably formed integrally therewith.

Two halves 17, 17 of the pattern are secured to the top side of the plate 5 and are connected by the runner 18 which form, in the sand, gates 20 to the pattern cavities.

The numeral 19 designates the boxlike flask. This flask has the end bosses 20, 20 provided with holes to receive the posts 4, 4.

In use the dogs 15 are swung outwardly into released position and the plate 5 is inserted into the frame 1 with the flange 7 engaged under the adjacent end rib 2 and with the lug 13 seated in the end notch 11. The dogs 15 are then swung inwardly underneath the flange 10, as shown in Figures 1 and 3 and the plate 5 is thus fastened securely in the frame with the end lug 14 fitting in the notch 12. The flask 19 is then seated on the frame with the posts 4 fitted through the holes in the lugs 20.

35 The flask is then filled with sand which is tamped closely around the patterns and runner. The flask with the tamped sand therein is then lifted off and another placed on the frame and filled with sand and tamped as before and the

40 two flasks then placed in coinciding relation so that the casting and gate cavities will register and two complete castings may be made at one pouring of the molten metal. This metal may be poured through a sprue provided in the sand 45 of one of the flasks and connected with the gates formed by the runner 18.

Two castings may thus be made by one pouring of molten metal whereas by the present method only one casting is made. This is true since by the method now commonly used one half of the pattern is secured on each side of a plate and therefore the plate must be reversed and two flasks tamped with sand to form a single casting cavity.

55 When the desired number of castings have been

made from any particular pattern the plate 5 may be removed and another plate with other patterns thereon may be substituted therefore for making a different type of casting.

It is, of course, to be understood that the halves of more than one pattern, connected by runners, may be secured to the top side of plate 5, and the production of castings correspondingly increased.

This type of pattern board may be easily 10 remounted in a molding machine and with the removable plate 5 will increase casting production without loss of castings due to misalignments.

What I claim is:

In a mold, a pattern board comprising, a frame 15 having an inside inwardly extending flange around the frame and spaced from the top thereof, a plate fitted closely within the frame and resting on said flange and whose upper face is flush with the top of the frame, a transverse 20 clamp secured to the under side of the plate, at one end thereof, and whose outer margin is spaced from the plate, said spaced margin engaging underneath the adjacent end flange of the frame, a transverse clamp secured to the bottom of the plate and spaced from the other end of said plate, and whose outer margin is

spaced from the plate, clamp dogs pivoted to the frame and whose free ends are engageable with and releasable from the spaced margin of the last mentioned clamp, handles on the pivoted ends of said dogs whereby the dogs may be moved into engagement with, or released from, said clamp, the outer margins of said clamps each having a central, outwardly flared notch, tapering lugs on the ends of the frame extending into said notches to hold the plate centered relative to the frame.
